UNITED STATES PATENT OFFICE

CYRUS PALMER STAM, OF FLORAL PARK, NEW YORK, ASSIGNOR TO OBERLY & NEWELL,
545 PEARL ST. CORP., OF NEW YORK, N. Y., A CORPORATION OF NEW YORK

ADVERTISING-DISPLAY DEVICE

Application filed February 1, 1929. Serial No. 336,712.

This invention relates to advertising display devices, and has for its primary object and purpose to provide a device of this kind for use in window or counter display advertising of commercial commodities which is simple and inexpensive in its construction, and may be easily and quickly set up in position for use or collapsed or folded so that its several component parts will assume a compact relationship whereby a large number of the articles may be conveniently stored in a relatively small space.

It is a more particular object of the invention to provide an advertising display device of this kind in which the several relatively foldable parts will automatically assume the correct relationship to each other for the arrangement of the advertised commodities in juxtaposition thereto by a single, simple manual operation in arranging the device in display position, and without requiring the subsequent manipulation of interlocking elements, easels, or other attaching or supporting members in order to retain the primary relatively foldable parts of the device in set up position.

More particularly, in one embodiment of the invention, the device consists of intermediate and side main display panels and a base section hinged to the lower end of each panel. The base sections are also hingedly connected with each other and the side panels are hinged to the opposite edges of the central display panel. The base panels may thus be moved to a position at right angles to the respective display panels to rest upon a counter or window floor merely by the movement of the side panels to a position in angular relation to the central display panel. Also when the device is folded or collapsed, it is only necessary to move the side panels inwardly whereupon the base sections connected therewith will be folded upon the base section connected with the central panel and said base sections will be closely confined between the side panels and the central panel in superposed relation.

It is also an additional object of the invention to provide a structure as above described which may be conveniently produced in a

single blank from heavy cardboard and having hingedly connected parts of the central panel and the base section which is connected therewith which are relatively movable when the device is set up to provide a convenient supporting shelf for the merchandise to be displayed.

With the above and other objects in view, the invention consists in the improved advertising display device and in the form, construction and relative arrangement of its several parts as will be hereinafter more fully described, illustrated in the accompanying drawings and subsequently incorporated in the subjoined claims.

In the drawings, wherein I have illustrated one simple and practical embodiment of the device, and in which similar reference characters designate corresponding parts throughout the several views,

Figure 1 is a perspective view showing a preferred form of the device as set up in position for use;

Fig. 2 is a similar view showing the device partly collapsed or folded;

Fig. 3 is a plan view illustrating the display device completely folded or collapsed;

Fig. 4 is a sectional view on an enlarged scale taken substantially on the line 4-4 of Fig. 3, and

Fig. 5 is a plan view of the cardboard blank from which the device is produced.

Referring in detail to the drawings, the display device is preferably formed from heavy cardboard, and as herein shown consists of a single blank cut from the cardboard sheet by means of a suitable die to provide a relatively wide central display panel 5 and the side display panels 6. These panels may be of any suitable length and width and at their upper ends have a predetermined ornamental contour. The cardboard is scored at the juncture of the panels 5 and 6 to provide flexible connecting hinge folds 7.

The central panel 5 at its lower end is provided with a projection which preferably tapers in width and forms a central base section 8, the cardboard being scored at the juncture of the base section with said panel to provide the hinge fold 9. Additional base

sections 10 extend laterally from the opposite edges of the central base section 8 and are connected therewith by the hinge folds 11. Each of these latter base sections is also 5 scored in parallel relation to one of its edges to provide a hinge fold at 12, said edge portion of the base section being adapted for attachment by a suitable adhesive to the outer or rear face of one of the side panels 6 at the 10 lower end thereof as clearly shown in Fig. 1 of the drawings.

The cardboard material is also provided with spaced parallel cuts or incisions indicated at 13 which extend into the central base 15 section 8 and into the lower end of the central panel 5. Between these cuts or incisions, the material is scored to provide the hinge folds indicated at 14, 15 and 16 respectively. Thus, between the hinge folds 14 and 16 the 20 material is scored along the hinge fold 15 to provide the relatively movable parts 17 and 18 respectively. It will thus, be seen that when the parts of the blank are positioned as shown in Fig. 1 and the base sections 10 permanently 25 connected with the lower ends of the side panels 6, the parts 17 and 18 assume positions at right angles to each other, the parts 17 constituting a supporting shelf positioned above the plane of the central base 30 section 8 and in parallel relation therewith.

It is of course, understood that in the use of such devices, the front surfaces of the panels 5 and 6 bear appropriate printed advertising matter, or lithographic illustrations 35 of various kinds descriptive of the use of the particular commodity to be advertised. In arranging the device in a show window or upon a counter, it is only necessary to move the side panels 6 from the folded position on the central panel as shown in Fig. 3 to the angularly 40 projecting position with respect to the central panel as seen in Fig. 1 in order to move the relatively foldable base sections 8 and 10 to a position in a common horizontal plane at 45 the lower edges of said vertical display panels, such operation resulting from the fact that the side base sections 10 have a permanent hinged connection with the lower ends of the side panels 6 so that said base sections 50 10 necessarily partake of the movement of said side panels, and in such movement also necessarily cause the downward and outward movement of the central base section 8 with which the sections 10 are hingedly connected. 55 Simultaneously, the shelf forming parts 17 and 18 connected with the central base section 8 at the central panel 5 assume positions in right angular relation to said panel and base section respectively. One or more of the 60 commodities to be advertised is then placed upon the horizontal shelf 17, the weight thereof of being wholly disposed in advance of the panel 5, effectually preventing the accidental overturning or collapse of the device and 65 maintaining the firm contact of the several

base sections 8 and 10 with the counter or the floor of the show window.

When the display is to be discontinued, it is only necessary to remove the articles from the shelf 17, and then by a slight pressure against the rear sides of the panels 6 fold the same inwardly upon the panel 5. In this inward movement of the side panels 6, owing to the angular relation of the hinge fold lines 11 and 12, the base sections 10 are automatically folded upwardly towards the inner sides of the panels 6, and of course the central section 8 is thereby also moved upwardly towards the central panel 5 as clearly illustrated in Fig. 2 of the drawings. In such movement of the central base section 8, the shelf forming parts 17 and 18 are also folded upon each other. Thus as the inward collapsing movement of the side panels 6 continues, it will be clearly evident that the parts 17 and 18 will be folded into closely superimposed relation to each other and upon the face of the panel 5 while the base sections 10 will be folded upon the base section 8 which also lies in closely superimposed relation to the panel 5 and the part 18 and finally the side panels 6 closely cover and confine the relatively foldable base sections and the parts 17 and 18 between said side panels and the central panel 5, as shown in Fig. 3 of the drawings. The relatively foldable parts thus are protected against mutilation or injury by the main panels 5 and 6, in the stacking of a large number of the devices upon each other for transportation or storage.

From the above description, it will be seen that I have provided an advertising display device which is capable of instant adjustment to its set up or collapsed position, and in which the several parts at all times remain in permanently connected relation with each other. By avoiding the necessity of more or less intricate manipulations of interlocking tabs, or other elements to be individually operated after the main parts of the device have been disposed in their proper relative positions, considerable time in the dressing of show windows may be saved, and undue straining of the cardboard parts with the possibility of tearing or otherwise mutilating the same it also obviated. It will further be appreciated that such a device may be manufactured and distributed by the producers of commercial commodities gratis to the retailers, at very nominal cost.

I have herein illustrated and described an embodiment of my present invention, which has given entire satisfaction in practical use. Nevertheless, it is to be understood that the essential features of the present disclosure are susceptible of embodiment in various other alternative structural forms, and I accordingly reserve the privilege of resorting to all such legitimate changes therein as may be

fairly embodied within the spirit and scope of the invention as claimed.

I claim:

1. An advertising display device comprising a single unit structure having a central display panel and side display panels hingedly connected with the central panel at its opposite edges, and a base section associated with each of the display panels and having an inseparable hinge connection with the lower edge of the central panel, and said base sections being hingedly connected with each other whereby upon movement of the side display panels from a superimposed position upon the base panel to a set up position in angular relation thereto, said base sections are automatically moved into a common horizontal plane, and additional relatively foldable parts integrally connected with the central panel and the central base section and automatically assuming a position in right angular relation to each other to form an article supporting shelf when the device is arranged in set up position.
2. A display device formed from a single blank of cardboard and comprising central and side display panels hingedly connected with each other and a base section having a permanent hinge connection with the lower end of each panel for folding movement relative thereto, and said base sections being also hingedly connected with each other and adapted to be moved into superimposed relation upon the central display panel by the inward folding movement of said side panels thereon to collapsed position, and said blank being cut along spaced parallel lines extending into the lower end of said central panel and said central base section and having parallel hinge scores between said cuts providing foldable parts adapted to assume a position in right angular relation to each other to provide a horizontal supporting shelf above said central base section when the device is arranged in set up position.

In testimony that I claim the foregoing as my invention, I have signed my name hereto.

CYRUS PALMER STAM.
